METHOD OF MAKING LOCK NUTS

I. C. Emery, Baltimore, Md., assignor to The Lock Nut Corporation of America, Chicago, Ill., a corporation of Delaware

Application November 21, 1932, Serial No. 643,759

17 Claims. (Cl. 10—86)

The present invention relates to a method of making lock nuts of the type having superposed wings joined by a neck.

Lock nuts of this general type are well-known in the art and several processes have been devised for making the same. One is claimed in my Patent 1,516,721 granted November 25, 1924.

Large numbers of lock nuts have been made by this patented process, and the nuts themselves, so far as the locking feature is concerned, are considered very satisfactory and desirable. However, the nuts were not bought in quantities anywhere near sufficient to supply the extensive market therefor, due to the fact that the cost of manufacture by this process was greater than desired.

It is one of the main objects of the present invention to provide a process whereby, when the lock nuts are made in substantial quantities, they can be manufactured at a cost only slightly exceeding the cost of making ordinary nuts.

The lock nuts made by my prior process had rounded edges at the outside of the neck. Although this did not affect the strength or locking qualities of the nut, yet there were some who objected on account of appearance. If sufficient pressures were employed, the outside surface of the neck could be squared up, but the cost of supplying the required high pressures was so great that, as stated, the lock nuts were left with the rounded edges. Again, it was necessary to make the nut from a blank having the grain running lengthwise thereof. In view of the method of making the nut, the stock or metal had to be selected very carefully, and even with selected stock, oftentimes the metal of the neck portion was strained or slightly cracked, and in any event was weakened because of being worked cold. Furthermore, the neck was too thin. Attempts were made to punch the holes in the blank used in my prior process before the bending step, but this was not successful, since the bending deformed the shape of the holes. Hence in my prior process it was necessary to form the holes after the bending operation. Even then these holes could not be punched for various reasons and had to be drilled.

It is another object of the present invention to overcome all of these defects.

Other objects and features of novelty will be apparent from the description taken in connection with the drawings, in which

Figure 1 is a perspective view of the front end of a strip of blanks from which the nuts are formed;

Figure 2 is a similar perspective view, showing the condition of the first blank after the first step of the process;

Figure 3 shows the blank after the narrow strip midway between the holes, or what may be termed the neck portion, has been heated;

Figure 4 is a diagrammatic elevational view, showing the blank in a die and after the plunger has bent the two wings of the nut about the heated portion;

Figure 5 is a view similar to Fig. 4, showing the plunger at the bottom of its stroke and after having squared up the outer surface of the neck and thickened the same;

Figure 6 is a perspective view of a lock nut 15 after it has been ejected from the machine of Fig. 5;

Figure 7 is a sectional elevation of the nut of Fig. 6 after the same has been tapped or threaded;

Figure 8 is a similar view after the two wings 20 have been pressed toward each other slightly;

Figure 9 is a diagrammatic elevational view, illustrating some of the instrumentalities used to make nuts according to the present process;

Figure 10 is a sectional elevation taken substantially on the line 10—10 of Fig. 9;

Figure 11 is an elevational view of a bent blank similar to that shown in Fig. 4 but made from a blank that has no groove or thinned portion; and

Figure 12, is a similar view, illustrating the 30 bent blank made from a blank having a groove but no projecting ridge like 24.

Lock nuts made by the present process are formed from sections of a long strip of metal rolled to a thickness the same as the wings of the nuts. The front end of such a strip is shown in Fig. 1, the portion used to make one nut being the metal between the dotted line 20 and the front end of the strip.

The first step of the process consists in forming the holes 21, one in the center of each wing 25 and 26. Preferably this is done by punching. For reasons explained hereinafter, it is desirable to thin the metal of the blank throughout a narrow strip extending transversely of the blank and located midway between the holes 21. This can be done in various ways. According to one method, the metal of the narrow strip is subjected to pressure, as by means of a plunger, forming a transverse groove 23. Preferably the sides of this groove are flat and perpendicular to the top surface of the blank, so that when the wings of the blank are bent downwardly from the positions shown in Fig. 3 to the positions shown in Fig. 4, the flat sides of the groove form the flat outer

40

50
55

surface of the neck of the nut. After the wings of the nut have been bent about the neck as a hinge, it is found that the metal at the neck usually is not thick enough or entirely properly disposed. To offset this, the bottom of the blank may be formed with a projecting strip 24 parallel with the groove 23. The groove and projecting strip are of such size as to leave the proper amount of metal in the neck so that when the outside surface of the neck is flattened and subjected to pressure, the neck portion itself will be somewhat thicker than in the nuts of this type heretofore made. Forming the groove and the strip in the manner outlined works the metal in the neck to some extent and thereby improves it.

The next step of the process consists in heating a narrow strip of metal disposed midway between the holes. Thus, as shown in Fig. 3, the neck portion 22 is heated and as far as possible the heating is confined to the neck. This is done by raising the temperature of the neck as rapidly as possible so that the heat cannot diffuse away through the metal. Perhaps this may be effected most easily electrically. Thus an electric conductor in contact with the ridge 24 and a reciprocating conductor above the blank may be employed, the latter being moved down into the groove and contacting with the bottom surface thereof. Of course both of the conductors would be suitably insulated. The neck is heated to such temperature that the wings can be bent easily around the neck as a hinge. The necks of nuts made by my prior process, where the bending was effected cold, were weakened because the metal was subjected to stresses greater than its elastic limit. Hence cracks and imperfections developed. With the present process, however, where the bending is effected with the neck heated to the proper temperature, the metal is not stressed beyond its elastic limit and hence no imperfections develop. On the contrary, the bending of the metal hot and the subsequent step of flattening the outer surface of the neck of the blank and squaring up the entire blank, works the metal in the neck and really improves its quality.

After the neck portion of the blank has been heated, the wings are turned downwardly, as viewed in Fig. 3, about the heated portion as a hinge to positions that are substantially parallel. The form of a blank near the end of this bending operation is shown in Fig. 4. As previously pointed out, it will be noted that the outer surface of the neck is substantially flat because the flat sides of the groove 23 really in effect preformed the flat outer surface of the neck after bending. The slight projection 42 is purposely provided so that the projection may be forced downwardly to thicken the neck in the next operation.

After bending the wings into the position shown in Fig. 4, the outside surface of the neck of the blank is smoothed and flattened, and the neck itself thickened. At the same time the entire blank is squared up so that the holes are in alignment.

The blank as ejected from the machine of Fig. 5 is shown in perspective in Fig. 6.

The blank is now threaded or tapped, giving the nut shown in Fig. 7.

Finally the two wings 25 and 26 are pressed slightly out of parallel to throw the threads of the two wings slightly out of position so that when the nut is screwed on a bolt the nut will be held against turning movement in a well-known manner.

According to the present invention, the process

is continuous, the blanks being moved from station to station and finally ejected in the form shown by Fig. 6. Thus referring to Fig. 9, there is there shown a die 27 along the top surface of which is fed the strip of blanks B from station to station or step by step. At the first station indicated by the dotted line 28, a head 29 having the punches 30 moves downwardly and forms the holes 21 in the blank. Where the metal of the neck 22 is to be thinned, the punch can be provided with the transverse pressure member 31, which will form the flat-sided groove 23 at the same time that the holes are punched. If it is desired to have the blank formed with the transverse strip 24, then the die 27 is provided with a slight depression 32 of proper shape to form this strip. Obviously the holes will be punched and the groove 23 and strip 24 formed simultaneously.

After this punching operation, the blank is fed along the top of the die 27 so that it now occupies the position indicated by the dotted line 33, a new blank being presented to the punch 29. In position 33, a narrow transverse strip of the blank is heated. For this purpose there are provided the electrical conducting members 34 and 35, both properly insulated and 35 being mounted for vertical reciprocation. Where the blank has a groove, the member 35 is moved downwardly into the same, forcing the ridge 24 into contact with the conductor 34. After the electric current has been on the proper length of time and the narrow strip rapidly heated to the desired temperature, the conductor 35 is moved upwardly and the blank advanced to the position indicated by the dotted line 36. Here a plunger 37 having a right angle edge 38 descends and the edge cuts off the blank 36 along the line 39, forcing the two wings of the blank downwardly into the recess 40 of the die. The neck or central transverse strip of the blank is supported on the upper surface of the narrow supporting strip 41 during this bending operation. After the plunger 37 has descended to near the bottom of its stroke, the blank will take the shape shown in Fig. 4, both wings having been bent about the neck while hot into substantially parallel positions.

If a blank is employed that has no thinned portion or groove, after the bending operation the appearance of the same will be as illustrated in Fig. 11. It will be noted that the thickness of the neck is the same as the thickness of the wings. Such bent blank can be squared up and the outer surface of the neck flattened by the operation illustrated by Fig. 5, but obviously it requires more work to do this than when a blank like that shown in Fig. 3 is employed.

Again, instead of a blank like that shown in Fig. 3, it is possible to use one that does not have the ridge 24, but only a groove 23. In this case, after the wings have been bent around the neck portion as a hinge, the form of the neck is as shown in Fig. 12. It will be noticed that there is a slight projection 55 of metal at the outside of the neck, and of course it requires more work to flatten the outer surface of the neck and square up the nut where this amount of projecting metal is present.

If the groove 23 and projecting ridge 24 are properly made, as shown in Fig. 3, there is only a very slight amount of the projecting metal 42 at the center of the outer surface of the neck. Hence very little work on the metal is required to square up the nut and flatten the outer surface of the neck. Furthermore, the projecting

metal 42 is desired because in the next step it is forced into position so as to thicken the neck.

In bending the wings around the top edge 41 of the support it is necessary that the top edge 41 be substantially flush with the top surface of the die and so positioned that the ends 44 and 45 of the wings will not be prevented from being forced into the positions shown by Fig. 5 by touching the bottom surface 46 of the die recess 40. With the edge 41 of the support in this proper position for bending the wings to nearly final position, it is found that there is not sufficient metal for the required strength at the neck of the nut. Furthermore, in the operation shown by Fig. 5, when the plunger 37 moves to its bottom position, the surface 47 of the plunger in flattening the outside surface of the neck of the nut would decrease the thickness of the neck. In order to overcome this defect and increase the thickness of the neck as compared to prior nuts of this type, the support is mounted for lateral sliding motion, as shown in Fig. 10. Thus if the support 48 is moved to the left so that the edge 49 thereof substantially contacts with the surface 50, then the supporting edge 51 will be brought under the plunger 37 and this edge will be somewhat spaced from the inner surface of the neck, as shown in Fig. 5. Of course the effect of withdrawing the supporting edge 41 could be obtained in other ways.

When the plunger moves from the position of Fig. 4 to that of Fig. 5, it puts pressure on the whole blank, thereby squaring up the blank and smoothing and flattening the outer surface of the neck. Furthermore, the projecting metal 42 is forced downwardly to thicken the neck portion. As the ends 44 and 45 of the wings rest on the bottom of the die and are forced thereagainst, both wings are properly positioned and as a result the holes 21 will be properly aligned.

When the plunger 37 is raised, the nut blank will stick in the recess of the plunger until it reaches its upper position, when it can be removed by a sidewise moving ejector.

While the nut blank is being bent into the form shown in Figs. 4 and 5, the metal at the neck, being hot, is being worked by the plunger, but the heat is dissipated through the blank into the plunger and by contact of the plunger with the heated neck portion. This cooling action is sufficiently rapid so that the portion of the metal at the neck is hardened, thereby increasing the strength and desirability of the final product.

It does not make any difference which way the grain runs in the blank fed to the machine for forming the nut, as the neck portion that is bent is heated and the bending is effected while the neck is hot. Where the bending is done while the neck is at an ordinary temperature, as taught by my prior patent, it has been found absolutely necessary to have the grain run lengthwise of the blank. In view of the fact that it is immaterial which way the grain runs in the blank, the strip of blanks can be made of a width as shown in Figs. 1, 2 and 3, or having a width equal to the dimension line 28 of Fig. 9. In the latter case the blanks would be fed through the dies in such manner that the bend would be made parallel with the grain of the blank.

Instead of forming the thinned transverse strip midway between the holes of the blank by the presser member 31 etc., this could be done in the mill rolling the strips of blanks, so that the blank as fed into the machine of Fig. 9 would have the thinned section already formed.

Although the invention has been described in

connection with forming a square nut, it is obvious that by suitably stamping or cutting the outline of the blank that hexagonal nuts could be made or nuts of other shapes.

It will be understood that where mention is made of heating the neck electrically that the conductors are in circuit with a supply of low voltage electricity and that the neck will be brought to the required temperature in a manner similar to spot welding.

Although one method of carrying out my invention has been described in detail, it is to be understood that it is not limited to the specific details, but includes modifications and changes which come within the scope of the appended claims.

Having thus described the invention, what is claimed as new and desired to be secured by Letters Patent is:

1. In the process of making metal lock nuts of the type having superposed wings joined by a neck, the steps of forming two holes in a flat blank, one in the center of each of the subsequently formed wings, forming a transverse groove in one face of the blank between said holes, heating the metal at the bottom of the groove, bending the two wings away from the groove and toward each other into spaced relation, squaring up the bent blank and flattening the metal on the outside of the neck thus formed, and cooling the heated part of the metal, thereby hardening the same.

2. In a process of the character described, forming a long strip of metal designed to be made into a plurality of lock nuts of the type having superposed wings joined by a neck, advancing said strip station by station, and performing on a section of the same sufficient to make a nut the following steps: one, while at the first station forming two holes in the strip, one in the center of each of the subsequently formed wings; two, while at the second station heating a narrow transverse strip of the blank substantially midway between said holes; three, while at the third station cutting off said section and bending the two like parts of the section about the heated part as a hinge to form the spaced wings connected by a neck.

3. The process according to claim 2 wherein the long strip is formed by rolling.

4. The process according to claim 2 wherein the step numbered one includes forming a narrow transverse groove midway between the holes.

5. The process according to claim 2 wherein the step numbered one includes forming a narrow transverse groove midway between the holes, said groove having flat sides substantially perpendicular to the face of the blank.

6. The process according to claim 2 wherein the step numbered one also includes forming a narrow transverse groove midway between the holes and a transverse rib parallel to the groove on the other face of the blank.

7. The process according to claim 2 wherein the step numbered three also includes applying pressure to the outside surface of the neck to flatten the same and square up the blank.

8. The process according to claim 2 wherein the step numbered three also includes rapidly cooling the neck to harden the same.

9. In the process of making nuts of the type having superposed wings joined by a neck, the steps of forming a long narrow strip with transverse grooves spaced equal to the length of a

blank that will form a nut, forming two holes symmetrically located, one on each side of a groove, heating the neck of metal adjacent the groove, severing the strip midway between adjacent grooves, and bending the severed portion about said neck as a hinge while hot to position the two wings in substantially parallel spaced relation.

10. The process according to claim 9 wherein the grooves have flat sides substantially perpendicular to the face of the strip.

11. The process according to claim 9 with the added step of applying pressure to the outside of the neck to flatten the same and square up 15 the blank.

12. The process according to claim 9 with the added step of applying pressure to the outside of the neck while the blank is in a die to flatten and thicken said neck and square up the blank.

20. 13. In the process of making lock nuts of the type having superposed wings joined by a neck, the steps of forming two holes in a flat blank, one in the center of each of the subsequently formed wings, pressing a narrow transverse strip of the blank midway between the holes to thin the blank at this region, heating said strip, and bending the blank about said strip as a hinge while the strip remains hot, thereby forming spaced wings connected by a neck.

30. 14. In the process of making metal lock nuts of the type having superposed wings joined by a neck, the steps of forming two holes in a flat blank, one in the center of each of the subsequently formed wings, heating a narrow trans-

35. verse strip of the blank substantially midway

between said holes, bending the blank about said heated strip as a hinge while said strip is hot, thereby forming spaced wings connected by a neck, applying pressure to the outside of the neck connecting the wings to flatten the same and increase the thickness thereof and square up the blank and rapidly cooling said neck to harden the same.

15. In the process of making lock nuts of the type having superposed wings joined by a neck, 10 the steps of forming two holes in a flat blank, one in the center of each of the subsequently formed wings, forming a narrow transverse groove midway between the holes and also a transverse rib parallel to the groove on the other 15 face of the blank, heating the narrow transverse strip of metal at the bottom of said groove, and bending the blank about said heated strip as a hinge while said strip is hot, thereby forming spaced wings connected by a neck.

16. The process according to claim 15 wherein said groove is formed with flat sides substantially perpendicular to the face of the blank.

17. The process of making nuts of the type having superposed wings joined by a neck consisting in taking a flat blank consisting of two like wings of uniform thickness connected by a narrow thinner neck, each wing having a centrally located hole therethrough, heating the thin neck portion, bending the blank about said 30 neck as a hinge while the neck remains hot, and applying pressure to the outside of the neck to increase the thickness thereof and square up the blank.

I. C. EMERY.
